UNITED STATES PATENT OFFICE.

GEORGE W. DONNING AND DAVID ALEXANDER DONNING, OF BRIDGEPORT, CONNECTICUT.

THERMOSTATIC DEVICE.

Application filed April 18, 1922. Serial No. 555,500.

This invention relates to thermostatic devices. The primary object of the invention is to provide a thermostatic device, utilizable in a variety of situations, of very simple 5 construction, but with a marked degree of efficiency.

A further object of the invention is to provide a thermostatic device, for use in connection with the internal-combustion 10 motors and the like, whereby certain devices associated with the motor may be operated in accordance with the thermal conditions of that motor.

With these and other objects in view, the 15 invention resides in the structure herein disclosed and in certain details thereof, as hereinafter more specifically pointed out and claimed.

In order that the invention may be more 20 readily comprehended, several embodiments of our improved thermostatic device are shown, but it is to be understood that the invention is capable of other embodiments, and is susceptible of a wide range of utilization.

In these drawings:

Figure 1 is a view partly in section and partly in elevation of our thermostatic device shown as mounted on the wall of a 30 structure, such as an internal-combustion motor, having a channel or water jacket for the passage of a cooling fluid;

Fig. 2 is a view in plan of the same;

Fig. 3 is a fragmentary detail view, partly in section, of a portion of the device embodying a valve-operating mechanism;

Fig. 4 is a fragmentary detail view in perspective of an air feeding mechanism;

Fig. 5 is a detail view in vertical section 40 of a fuel valve;

Fig. 6 is a fragmentary detail view in side elevation of a portion of the device shown in Fig. 3;

Fig. 7 is a detail view in top plan of an 45 electric switch and operating mechanism;

Fig. 8 is a similar view of a thermostatic coil and shaft;

Fig. 9 is a view in perspective of a portion 50 of the device;

Figs. 10, 11 and 12 are detail views in side elevation of certain elements of the device;

Fig. 13 is a view in vertical transverse section of a modified form of structure, showing a somewhat different type of thermostatic device mounted, in this instance,

on the head of a motor and in proximity to the firing chambers thereof;

Fig. 14 is a similar view of another type of thermostatic device; and

Fig. 15 is a similar view of a still different type of thermostatic device mounted on a motor.

Referring to these drawings, and to Figs. 1 to 7 thereof, the reference-character 1 designates the upper portion or head of an internal-combustion motor, of any appropriate type, having the usual water jacket or channel 2 for the passage of water or the like constituting a component of the motor-cooling system.

Mounted in the head, in this instance, or any other preferred portion of the motor where the cooling fluid or temperature of the motor may be effective thereon, is our improved thermostatic device 3. This is adapted primarily to be influenced by thermal conditions of the cooling fluid 4 in the jacket as the fluid, itself, may be influenced by thermal conditions of the motor.

The thermostatic device 3, in this particular embodiment, preferably comprises a housing 5 of any appropriate design and dimensions, and which is to be secured to the motor in any desired or required manner. The housing is formed with an internal chamber 6 in which is disposed an element 7 of thermostatic material and shown, in this instance, in the form of a coil, one end of which is secured to a shaft or arbor 8 which extends through the housing. Adjacent one end of this shaft is a short arm 9, carrying a set-screw 10, and adapted to engage lugs 11 and 11^a outstanding from the side of the housing and serving to limit rotary movement of the shaft in one direction as the same is actuated by the coil under varying thermal conditions which influence it.

The thermostat-coil 3 has its outer end attached to a threaded or screw member 6^a turning therein and in a bearing 6^b at the side of the housing and carrying a head 6^c provided with graduations or temperature-indicating markings 6^d with which cooperates a pointer 6^e outstanding from the housing.

This member 6^a constitutes an adjusting or tensioning device by which the thermostat may be set for action at any predetermined degree of temperature. The screw-member

6^a carries in this instance two adjustable nuts 6^c and 6^d, one of which (6^c) is within the housing and stationary on the member 6^a and engageable with either the bearing 6^b or a lug 6^e on the inside of the housing. By these means, rotary movement of the screw-member in each direction of its rotation is limited and the adjustment of the coil within the indication on the screwhead 6^c is maintained. The nut 6^c, outside of the housing, functions to lock the screw-member at any particular setting. By adjusting the screw-member in one direction, the coil is set to act "late", and if adjusted in the opposite direction, it acts "early".

On the end of the shaft 8 is a lever or actuator 12, to which is connected an arm 13 which, in turn, may be connected to any of a plurality of operable parts of sundry types of structures, such, for example, as port-closing valves 14, 14^a of a vaporizer-fuelizer 15, shown in Figs. 3 and 6, and more fully disclosed in the co-pending application of George W. Donning, filed April 18, 1923, Serial No. 554,684; or in connection with a valve 16 for controlling a device 17 adapted to supply air to a carburetor 18, as shown in Fig. 4, and likewise disclosed in the aforementioned Donning application; or in connection with a fuel-controlling valve 19 working in a fuel-nozzle 20, as shown in Fig. 5; of a carburetor (not therein shown); or in connection with an electric switch 21, as shown in Fig. 6, and wherein the member 12^a may be the actuator 12 of Fig. 1 but constituting a part of the switch.

The bottom or lower portion of the housing is provided with an opening 22, preferably rectangular, and through this a portion of the coil 7 extends so as to occupy a position within the effective zone of the cooling-fluid 4 of the water jacket 2. Inasmuch as it is not altogether desirable to have the coil in direct contact with the cooling-fluid, the same is, in this embodiment, separated therefrom by an instrumentality, shown in this instance as a sheath 23, secured to or forming an integral part of the lower portion of the casing 5. As shown in Fig. 1, the sheath is arc-shaped to correspond to the general curve of the coil. It may be of any appropriate material, provided such material is a good heat conductor. It will be understood that the sheath 23 normally occupies a position in the cooling-fluid and, taking the temperature thereof, transmits the thermal conditions of the fluid to the coil which, acting under the influence thereof, effects a rotatory motion of the shaft 8 to actuate the lever 12 and this, in turn, operates the connecting-arm 13 to cause a functioning of any of the instrumentalities hereinabove referred to (as well as others) actuatable thereby. At this point, it should be stated that instead of the

connection to these instrumentalities being through the actuator 12 and connecting-arm 13, the shaft or actuator may be directly connected to such instrumentalities to effect a more immediate action thereof.

In practical use, this type of thermostat has been found to be particularly efficient for automatically controlling sundry devices and instrumentalities employed in connection with automobiles, for operating valves in carburetors, in fuelizers, indicators, signals, etc.

In Fig. 14, we have shown a somewhat different form of thermostatic device which is, however, therein illustrated, as in the first embodiment, as being mounted upon a portion of a motor 1 and in a position to be influenced by the fluid of the motor-cooling system passing through the channel 2 in proximity, as usual, to the firing chambers 24 of the motor. In this embodiment, the thermostatic device includes a casing 25, preferably and as shown, arc-shaped, which is secured, as by tap-screws 26, to the motor, and with an interposed gasket 27 to prevent leakage of the cooling-fluid. In this embodiment, as in the one first described, there is an arc-shaped sheath 28 which is secured to the flanges 29 of the casing 25. Within a chamber 30 formed by the arc-shaped casing 25 and the sheath 28 is a thermostatic coil 31, the inner end of which is secured to a shaft or arbor 32, while its outer end is connected to a slide-plate 33 which seals a slot 25^a in the top of the casing 25 in which a bolt 34 works, the bolt being secured to the slide-plate and carrying on its outer end a wing-nut 35. The function of the nut is to lock the plate in any of a plurality of adjustable positions, which positions may be those indicated by graduations or markings 36 with which a pointer 37 carried by the nut 34 is adapted to engage. The graduations or markings indicate particular temperature degrees at which an initial start, say, is to be made.

The action and function of the thermostatic device of this second embodiment are substantially the same as those of the first-described embodiment.

In Fig. 13 we have disclosed a somewhat different type of structure: In this instance, the water jacket 38 is provided with an aperture 39 into which a threaded bushing 40 is projected, this being adapted to secure the thermostatic device 41 to the motor 1; there being a gasket 42 interposed between the upper surface of the jacket and the bottom of the thermostat housing. In order to maintain the thermostat rigidly on the motor, a set-screw 43 is threaded through a flange 44 of the casing and into the motor-head. In this instance, the thermostat 41 includes a fluid chamber 45 communicating with the channel 38 and pro-

vided in its upper portion with an outlet or vent controlled, in this instance, by a screw 46. The thermostat also includes a second chamber 47 in which is housed a thermostat-

5 ic coil 48 which is secured at its inner end to a shaft 49 and at its outer end to a fastening device 50. In order to limit the extent of rotative movement of the shaft, a stop 51 is secured to the shaft and abuts 10 against a lug 52 on the thermostat casing. In this construction, the cooling-fluid from the motor passes into the chamber 45 and imparts its thermal condition to the partition 53 which divides the casing into the 15 chambers 45 and 47. Thereby, the thermostatic coil 48 is affected, and this produces rotative movement of the shaft 49.

In Fig. 15 a still further embodiment is disclosed: In this instance, the thermostatic device 54 includes a casing 55 provided with a fluid-channel 56 communicating with the channel 57 of the motor-cooling system. The channel 56 surrounds a chamber 58 in which a thermostatic coil 59 is disposed. One end 25 of this coil is secured to a shaft or arbor 60, while the other end is secured to an adjusting member 61 which extends outside of the casing and is provided with a knurled head 62 having temperature graduations or 30 markings 63 with which cooperates a pointer 64 outstanding from the side of the casing. In the top of the casing is a vent or opening 65 which, in this instance, is normally closed by a threaded member 66. It will be understood 35 that the cooling-fluid in the motor is permitted to flow through the channel 56 of the thermostatic device and thereby influence the coil 59 to effect rotative motion of the shaft 60 and thereby actuate the parts 40 connected thereto. As in the other embodiments herein disclosed, the threaded member 61 permits the required tensioning of the coil 59 to predetermine its action, as explained.

45 In the different embodiments herein disclosed, the thermostatic coil is water jacketed, so to speak; that is, in the constructions disclosed in Figs. 1, 2, 9 and 14, the sheath 23, occupying a position in the cooling-fluid of the motor, separates that fluid from the coil; the fluid being jacketed about a portion of the coil. In the structure of 50 Figs. 14 and 15, the jacket is formed in the casing about the coil.

55 From the foregoing description, it will be perceived that we have presented a thermostatic device, in various forms, which is well adapted for use wherever it is desired to control instrumentalities or mechanisms for 60 variable thermal conditions.

What we claim is:

1. A thermostatic device including a housing, a coil adjustably supported therein and constructed of a thermostatic material sensitive to thermal conditions, the housing

adapted to space the coil from a body of fluid by which the coil is to be influenced, and an actuator independent of the housing connected with the coil and operable thereby.

2. A fluid-operated thermostatic device including a housing, a thermostatic element operatively mounted therein, a portion of the housing adapted to maintain said element in juxtaposition to but separated from a body of operating fluid, and means supported by the housing and in contact with the element for tensioning the same to vary its action.

3. A fluid-operated thermostatic device including a housing, a thermostatic coil therein, a portion of the housing adapted to separate the coil from a body of operating fluid surrounding said portion, a coil-adjusting device extending through the housing and connected to the coil, and means for locking 80 the adjusting device in adjusted positions to the housing.

4. A fluid-operated thermostatic device including a housing, a thermostatic coil therein, a portion of the housing adapted to separate the coil from a body of operating fluid surrounding said portion, a coil-adjusting device extending through the housing and connected to the coil, means for locking 90 the adjusting device in adjusted positions to the housing, and means associated with the adjusting device for indicating the setting 95 thereof.

5. A fluid-operating thermostatic device including a housing, a thermostatic coil 100 therein, a portion of the housing adapted to separate the coil from a body of operating fluid surrounding said portion, a coil-adjusting device extending through the housing and connected to the coil, means for locking 105 the adjusting device in adjusted positions to the housing, and means associated with the adjusting device exteriorly of the housing for indicating the setting thereof.

6. In combination, a support provided 110 with a channel for an operating fluid, a thermostatic device associated therewith and including a housing partially set into the channel and a thermostatic coil within the housing, a portion of said housing maintaining said coil in juxtaposition to but out of contact with said operating fluid.

7. In combination, a support provided 115 with a channel for an operating fluid, a thermostatic device associated therewith and including a housing partially set into the channel and a thermostatic coil within the housing, an actuator connected to and operable by the coil, means for limiting the extent of movement of the actuator, and means 120 for adjusting the coil to operate said actuator at a predetermined temperature of said fluid.

8. A structure of the kind described including a support provided with a channel 130

- for the heating of a cooling fluid, a thermostatic device associated with the support and including a housing, a thermostatic element within the housing and influenced by the fluid in the channel, an actuator connected to the element, means for predetermining the movement of the actuator under the influence of the element, and adjusting means carried by the housing for regulating the element to move at a predetermined temperature of the fluid in the channel. 65
9. A structure of the kind described including a support provided with a channel for the heating of a cooling fluid, a thermostatic device associated with the support and including a housing, a thermostatic element within the housing and influenced by the fluid in the channel, an actuator connected to the element, means for predetermining the movement of the actuator under the influence of the element, adjusting means carried by the housing for regulating the element to move at a predetermined temperature of the fluid in the channel, and temperature-indicating means associated with the element for denoting the temperature at which its initial movement shall be effected. 70
10. A structure of the kind described including a support provided with a channel for the heating of a cooling fluid, a thermostatic device associated with the support and including a housing, a thermostatic element within the housing and influenced by the fluid in the channel, an actuator connected to the element, means for predetermining the movement of the actuator under the influence of the element, adjusting means carried by the housing for regulating the element to move at a predetermined temperature of the fluid in the channel, and means for locking the adjusting device in a predetermined position. 75
11. A thermostatic device comprising a housing, a thermostatic coil disposed therein, a shaft connected to one end of the thermostatic coil to be operated thereby, an adjusting device connected to the other end of the coil and extending through the housing to permit movement thereof externally of the housing, and means for locking said adjusting device in any of a plurality of adjusting positions. 80
12. A thermostatic device comprising a housing, a thermostatic coil disposed therein, a shaft connected to one end of the thermostatic coil to be operated thereby, an adjusting device connected to the other end of the coil and extending through the housing to permit movement thereof externally of the housing, means for locking said adjusting device in any of a plurality of ad- 85
- justing positions, and an indicator associated with the adjusting device for predetermining the degree of adjustment of the coil. 90
13. A thermostatic device including a housing provided with an opening in its lower portion, a thermostatic coil supported in the housing and extending through said opening, a shaft journaled in the housing and connected to one end of the coil to be operated thereby, a stop on the shaft for limiting the extent of movement thereof in one direction, an actuator carried by the shaft and movable thereby, an adjusting device connected to the other end of the coil and extending through one wall of the housing to permit manipulation thereof externally of the housing, and means carried by the adjusting device and engageable with the housing for locking the device in any of a plurality of adjustable positions, said adjusting device comprising a threaded member, a thumb member graduated in degrees of temperature, and a pointer carried by the housing and disposed in relation to the thumb member. 95
14. A fluid-operated thermostatic device including a housing, an element therein of thermostatic material, means associated with the housing and juxtaposed to the element for maintaining it separated from a body of operating fluid, means supported by the housing and in contact with the element for tensioning the same to vary its action, and means for locking the tension device in a set position. 100
15. A fluid-operated thermostatic device including a housing, an element therein of thermostatic material, means associated with the housing and juxtaposed to the element for maintaining it separated from a body of operating fluid, means supported by the housing and in contact with the element for tensioning the same to vary its action, and an indicator associated with the tensioning means for denoting the degree of tension at which said element has been set by the tensioning means. 105
16. A thermostatic device, a thermostatic coil, a shaft connected to one end of the coil to be operated thereby, an adjustable device connecting with the opposite end of the coil, means for limiting endwise movement of the adjustable device, and separate means for locking said device in one of a plurality of positions. 110
- In testimony whereof we affix our signatures.
